ANGULAR ATTACHMENT FOR DENTAL
HANDPIECES

Walter John Terry, Seattle, Wash.

Application May 23, 1933, Serial No. 672,386

17 Claims.

(Cl. 32—27)

The invention is an improvement in angular attachments for handpieces for dental or other purposes which is constructed so that all workable parts may readily be removed for cleaning and renewing by one inexperienced in the art, and in which all of the delicate parts are fitted in their proper relative positions by skilled factory mechanics, and supplied in fully assembled units so that they may be instantly installed in the handpiece.

In most instruments of this type it is practically impossible to take the instrument apart and, therefore, the interior parts are not readily accessible so that it is very difficult to completely clean the instrument and, as parts wear, it is very difficult to remove and replace them, and in some cases impossible, therefore, when it is necessary to repair instruments of this type the instrument is generally returned to the factory, as it requires a skilled mechanic to remove and repair its parts. These instruments are also generally constructed so that wear develops in the frame or casings, and in some cases it is necessary to supply a new part or even a whole casing.

Instruments have been provided in which one part may be separated from another, and also in which some of the interior parts may be removed, and in some cases the rotating shafts have been removed from the frame, however in all instances these have been so constructed that they cause a direct wear in parts of the frame so that it is necessary to replace the frame or parts thereof.

This invention relates to an instrument in which all of the interior parts are supplied in separate and independently assembled units, each of which may be independently removed and replaced by a new complete unit. These units may be supplied, assembled and ready for use so that any one, even though he may be inexperienced in handling instruments and not mechanically inclined, may open an instrument, remove any of the parts, replace the parts and reassemble the instrument. These parts are also designed so that the bearings are removable, therewith, and, therefore, all wear in the casing or frame is eliminated. The head of the instrument is so arranged that the parts are formed in a removable barrel with both the upper and lower bearings and both of these bearings with all of the interior parts may be removed as a unit or in two units.

The object of this invention is, therefore, to arrange all of the interior or working parts of an instrument of this type so that any of the moving parts do not contact the frame or casing, and

also so that all of the interior parts may readily be removed and replaced, and in which the removable parts that require special fitting are contained in separate units which may be made in the shop.

Another object of the invention is to provide a dental handpiece which is substantially about one-half of the weight of normal handpieces so that a much more sensitive reaction to the drill contact or touch may be obtained which is essential to dentistry of the finer type.

Another object is to provide an instrument of this type in which all the parts may be removed and replaced by hand and by one inexperienced in mechanics or devices of this nature.

Another object is to provide an instrument of this type in which all the interior parts may be supplied independently and any one may be removed and replaced independently of the other.

Another object is to provide an instrument of this type in which the moving parts do not engage the frame or casing, and all exterior corners are rounded.

Another object is to provide a sliding bur lock for handpieces that eliminates all open holes thru the head, which leak oil and permit saliva to be drawn into the interior.

A further object is to provide an angle attachment for dental handpieces in which the top bearing of the head spindle is readily replaceable by the dentist and the front or main bearing of the head spindle is held in the head without threads being cut on the bearing or in the head.

And a still further object is to provide an angle attachment or handpiece for dental or other purposes in which all of the wearing parts and also all of the other interior parts are readily replaceable, which is of a simple and economical construction.

With these ends in view the invention embodies an angle attachment or handpiece having a head, a rear case and an angle section connecting the head and case in which each of these parts is a separate and independent unit and in which the interior operating parts are provided in three separate and distinct units, each of which may readily be removed and replaced independently, and also in which the head unit may be removed and replaced as an integral unit or in separate parts. The head unit is of a barrel shape with the front and back bearings contained in a removable sleeve or barrel in which the front bearing and spindle may readily be removed and replaced without removing the barrel.

Other features and advantages of the invention

will appear from the following description taken in connection with the drawing, wherein:

Figure 1 is a view showing an elevation of the instrument.

5 Figure 2 is a similar view on a large scale showing a longitudinal section thru the assembled instrument.

Figure 3 is a detail showing the head of the instrument.

10 Figure 4 is a similar detail showing the angle section of the instrument.

Figure 5 is also a similar detail showing the rear case of the instrument.

15 Figure 6 is a view showing the barrel as an assembled unit removed from the head.

Figure 7 is a view showing the gear assembly of the head and angle section.

20 Figure 8 is a view showing the operating gear and bearing removed from the rear case.

25 Figure 9 is a plan view of the barrel removed from the head of the instrument.

Figure 10 is a view showing one side of the barrel with the lower cap removed.

30 Figure 11 is a detail showing the head spindle with part broken away.

Figure 12 is a detail showing the front bearing removed from the lower end of the head spindle.

35 Figure 13 is an enlarged view with parts broken away showing the barrel removed from the head with all the parts therein.

Figure 14 is a cross section on line 14—14 of Figure 2.

40 Figure 15 is a view of a head of an old type of instrument showing the manner in which the head may be bored out to accommodate the barrel of the head as shown in Figures 6 and 13.

45 Figure 16 is a detail showing a cross section thru the bearings shown in Figures 7 and 8 showing an alternate design in which the bearings are made in two halves so that they may readily be removed from the spindles and replaced.

50 Figure 17 is a view similar to that shown in Figure 15 showing the upper bearing of the head in which the lower bearing is threaded in the head and the barrel shown in Figure 6 is omitted.

55 Figure 18 is a view showing a straight or plain R/4 attachment or handpiece in which the angle section is omitted, showing that the interior head construction, as shown in Figure 2, may also be used in a handpiece of this type.

60 In the drawing the numeral 1 indicates the head, numeral 2 the angle section and numeral 3 the rear case.

65 Figure 15 is of a different type and it will be noted that the vertical opening 5 of this head has been machined out to accommodate the barrel, as shown in Figure 6, and a screw opening 6 drilled and tapped therein to hold the barrel, the head is otherwise the same as is normally used for instruments of a different type. Other instruments of different types may also be machined or bored to accom-

modate the barrel of this device or any of the other parts.

70 The head 1 may be provided as shown in Figure 3 with a cylindrical section 7 having an opening 8 therein, and a horizontal section 9 having an opening 10 therein. At the upper end of the opening 8 is a partition 11 having an opening 12 in the center thereof thru which the upper end of the vertical spindle passes, and above this opening is a groove 14 in which a plate 15 is slidably held. The forward end of the plate 15 is provided with a slot 16 thru which the upper end of a bur passes and it will be noted that the edges of the slot 16 slide into a continuous ring around the upper end of the bur. The upper end of the bur above the ring passes into a recess 17 in a member 18 which is held upon the upper surface of the plate 15 by a screw 19. The member 18 fits between the edges of an opening 20 in the top of the head, as shown in Figure 14 and the upper surface of the member 18 is provided with teeth 21 by which it may be drawn backward from the position shown in Figure 2 to that shown in Figure 3, and the opposite end of this member is provided with a raised portion 22 which provides a cover for the recess 17. It will be noted that this sliding member, which engages and holds the upper end of the bur forms a complete seal for the top of the head, thereby eliminating all open holes thru the head which leak oil into the head and also allow saliva to be drawn on the inside. The upper side of the plate 15 is provided with a lug 23 which extends into a recess in the under side of the member 18 below the teeth 21, as shown, and it will be noted that this lug will prevent the plate 15 being placed in the head upside down as the lug will engage the surface at the bottom of the slot 16. This surface of the slot 16 is also provided with a recess 24 into which the end of the screw 19 extends and it will be noted that the screw will engage the end of the recess to limit the outward movement of this member with the screw in place. The plate 15 is bent slightly laterally to provide sufficient friction to restrict the movement of this member in the slot. It will be understood that any other means may be used for securing or locking the sliding member in any position in the head.

75 The horizontal section 9 of the head extends outward and the end thereof is provided with a flange 25 having teeth 26 in the outer edge thereof and a recess 27 formed inside of the teeth. This recess engages a collar 28 on the bearing 29 of the gear assembly shown in Figure 7, in order to govern the mesh of the gears to obtain perfect adjustment. A coupling 30 is freely mounted on the end of the section 9 and prevented moving off thereof by the flange 25, as shown in Figures 2 and 3 and it will be noted that as this coupling is screwed on threads 31 of the angle section 2 it will securely hold the angle section against the end of this horizontal section of the head with teeth 32 meshing with and holding in the teeth 26 at the end of the head. With these parts held the collar 28 will be held between the members 1 and 2 and the end of the member 2 is also provided with a recess 33 into which one side of the collar 28 will extend and by which it may be held.

80 The bearing 29, upon which the collar 28 is fixedly mounted is therefore held stationary in the opening 10 of the horizontal section of the head 1 and a bearing 34 is similarly held in an opening 35 in the angle section 2. The opposite end of the angle section 2 is bent upward from the point 36 and the outer end is provided with 75

opening 37 having a threaded section 38 therein, a recess 39 beyond the threaded section and an opening 40 beyond the recess. This end screws over a threaded nipple 41 on the end of the rear case 3 and the interior of the case 3 is provided with an opening 42 in which a bearing 43 of the operating gear 44 may be held. The upper part of the case 3 is provided with an enlarged opening 45 into which an end of a straight handpiece or flexible drive shaft may be inserted to engage and drive a shaft 46 extending thru the bearing 43 and upon which the gear 44 is fixedly mounted. The upper end of case 3 may be provided with a slot 47 by which it may be held by a wrench or the like while screwing it into or out of the angle section 2. The bearing 43 is provided with a stationary collar 48 which fits into the recess 39 of the angle section 2 which holds it rigidly against the end of the nipple 41 when the parts 2 and 3 are held together. The gear 44 meshes with a gear 49 at one end of the gear assembly shown in Figure 7 and gear 49 is fixedly mounted upon a shaft 50 which extends thru the bearings 29 and 34 and is provided with another gear 51 at the opposite end which meshes with a gear 52 on the vertical head spindle 13. The gear 52 is made integral with the spindle and it will be noted that the upper end of the spindle is rotatably mounted in a bearing 53 in the upper end 30 of a barrel 54 and the barrel and bearing are rigidly held in the casing by a screw 55 in an opening 56 as shown in Figure 2. The lower end of the spindle is rotatably mounted in a bearing 56, shown in Figure 12 and this bearing is held stationary by a cap 57 which is screwed on threads 58 at the lower end of the barrel 54 which engages and holds a flange 59 at the lower edge of the bearing against the end of the barrel. The flange 59 is also provided with notches 60 which fit over projections 61 at the lower end of the barrel to positively hold the bearing in relation to the barrel. The upper portions of the barrel and bearing 53 are provided with a flat side as shown in Figure 9 which provides clearance for the teeth of the gear 51, thereby permitting this gear to mesh with the gear 52. The vertical spindle 13 is provided with a central opening 62 in which the shank of a bur is held, and the upper end of the opening is provided with a lug 63 which 40 engages a recess in the side of the bur to insure its rotating with the spindle. It will be understood that any other means may be used for keying the bur to the spindle to insure its rotating therewith. It will be noted that by removing the screw 55 the entire barrel and interior assembly of the head may be removed, and by removing the cap 57 with the screw 55 in place the spindle 13 and front bearing 56 may be removed from the barrel. With the members 1, 2 and 3 separated, the gear assembly shown in Figure 7 may readily be withdrawn from the parts 1 and 2 and the unit shown in Figure 8 may readily be withdrawn from the lower end of the case 3 so that all of the interior parts may readily be withdrawn and replaced independently of the other. It will also be noted that all accurate machine work is well fitted in the units so that anyone, even though he may be inexperienced with devices of this nature may readily remove and replace them in order to clean or renew any part or parts.

It will be understood that changes may be made in the construction without departing from the spirit of the invention. One of which changes

may be in the use of the assembled parts with variations therein in an instrument, tool, or device of any other nature or for any other purpose, another may be in use of other means for holding or attaching the parts together, another may be in the use of other means for holding the barrel in the head as it may be held by friction or other means, another may be in the use of other means for holding the bearings and spindle in the barrel, and still another may be in the use of other means for holding the upper end of the bur or sealing the upper end of the head.

The construction will be readily understood from the foregoing description. In use the device may be provided as shown in an angle handpiece 15 for dentists, however, it will be understood that it may be also used in any other type of device, and for any other purpose. It will be noted that the handpiece is provided in three pieces, a head, an angle section, and a rear case, and the angle section is held to the head by the coupling 30, and the rear case is screwed into the end of the angle section. The interior parts of the head are provided assembled in a barrel, and inserted in the head as a unit and the entire unit is held by a 20 screw 55, which holds it rigidly in the head. The gear assembly is inserted in the horizontal section of the head with one of the gears meshing with the gear 52 and the collar 28, which governs the mesh of the gears, is locked against the end of the horizontal section of the head by the end of the angle section when the two are held together by the coupling. The operating gear assembly is placed in the rear case with the gear 44, meshing with the gear 49, and as the shaft 46 is rotated 25 it will rotate the shaft 50 and the spindle 13 thru the gears. The device may therefore operate as a complete unit, whereas, each part forms a separate and independent unit which may be removed and replaced independently of the other units. Any part thereof may readily be removed and 30 replaced, and the only tool required is a screwdriver which may be used to remove the screw 55.

With an instrument formed in this manner all of the internal or operating parts are provided in three separate and distinct units, each of which may be supplied as a separate unit and each of which may be removed and replaced independently of the other units without changing any part or parts of the instrument casing. Each of the units is also self-contained and provided with 45 complete bearings so that all working and wearing parts may be removed and replaced with the unit. The casing, therefore, only forms a housing for the units so that the life of the casing is infinite and as the units forming the internal parts thereof are readily renewable, the life of the entire instrument is also infinite. An instrument of this type also has many advantages as it is not necessary for the dentist to use an instrument in which the internal parts are worn as the cost of the interior units is comparatively small and he will be inclined to keep all instruments in comparatively perfect condition. The general appearance of the instrument may also be maintained in comparatively perfect condition as the necessity of using tools on the different parts which mar the surfaces thereof is eliminated as all the parts may readily be opened by hand and the interior units removed and replaced 50 by hand.

Although there is an advantage in providing the gears in the handle and horizontal section so that they may be readily removed there is a decided advantage in providing the head with a 55

complete removable barrel that contains both of the bearings of the spindle and also the spindle. This unit is so constructed that it is also possible to remove and replace the bearings without renewing the barrel or other parts thereof and as practically all of the wear in an instrument of this type is in the spindle bearings that hold the bur and as these bearings are comparatively small and inexpensive they may be removed and replaced as often as desired in order to maintain the instrument in perfect condition.

The barrel is held in the head by a screw, however, it may be held by friction or by any other means and it will be noted that the cap 15 at the lower end is threaded on the end of the barrel so that it is not necessary to cut threads on the bearing or in or on the head. The barrel may, therefore, be removed with the cap in place, or the cap may be removed so that the front 20 or main bearing, and also the spindle, may be removed without removing the barrel. The cap is threaded on the lower end of the barrel and the lower edge of the threads may be cut away, or slightly beveled as shown in Figure 10 so that 25 the finger nail or a sharp edge may be inserted therein to pry the bearing out of the barrel. This may, however, be removed by any other means. It will, therefore, be noted that all details of construction are made so that any part of the spindles, bearings, or housings, may readily be removed or replaced by hand and by anyone, even though he may be inexperienced in instruments of this nature or description.

The sliding bur lock at the top of the head is 35 also an improvement as it makes it possible to eliminate all open holes thru the head which leak oil and also permit saliva to be drawn into the head, which causes rust and, therefore, increase wear on the internal parts. The sliding bur lock makes it possible to completely seal the 40 head of the instrument which at the same time provides a very neat and compact appearance.

The head has been referred to and described as a one-piece head, whereas it will be noted that 45 it is formed from three pieces, the head proper, the tube section, and the nut, however, the three pieces form one complete unit and are inseparable as the nut is placed over the tube section and then the tube section is pressed into the head 50 where it is permanently held and may be sealed or secured in any manner. It will be understood, however, that the head may be formed in any manner and may be of any design. The bearings 55 29 and 43 have also been referred to as parts of single units shown in Figures 7 and 8, respectively, however, it will be understood that these bearings are also separate pieces and are permanently secured on the spindles.

The bearings may, however, be provided in two 60 halves, as shown in Figure 16, and these halves may be placed over the spindle and clamped in the casing. It will also be noted that all bearings in the handle and head are rigidly clamped in place by the parts of the handpiece as they are 65 assembled and these bearings, therefore, remain stationary as the handpiece is used as they are firmly clamped against parts of the casing.

The entire construction of this device makes it 70 possible to reduce the weight of the casing so that the entire instrument weighs about one-half of instruments of this type and a light weight instrument makes it possible to work with a higher degree of efficiency as its reaction to the drill contact or touch is much more sensitive. This 75 particular construction and arrangement of the

parts provides a handpiece with many advantages as compared to any handpiece now in use.

Having thus fully described the invention what I claim is new and desire to secure by Letters Patent, is:—

1. An angle handpiece for dental use, or other purposes, comprising a head, an angle section, and a rear case, connecting means for said parts, a spindle having a gear thereon, a barrel in which said spindle is rotatably mounted, said barrel having bearings at both ends thereof assembled therein and adapted to be removed as a unit therewith, means holding said barrel in said head, said barrel adapted to be removed with the spindle and bearings therein as a unit, a gear assembly 10 rotatably mounted in said angle section and adapted to rotate said spindle thru the gear thereon, said barrel having a flat side corresponding with the gear of said gear assembly, thru which said gear passes as the barrel is removed with the gear assembly in position, said gear assembly also adapted to be removed and replaced with the barrel in position in the head, and an operating gear assembly removably held in said rear case.

2. In an angle handpiece having a head and a handle removably attached to said head, a spindle, a barrel in which said spindle is rotatably mounted, a front bearing in said barrel, a cap holding said front bearing in said barrel, an inner bearing, means for holding said inner bearing and said barrel in said head, and gearing adapted to drive said spindle thru said handle.

3. An angle hand piece having a head and a handle removably attached to said head, a spindle mounting removably held in said head, a gear assembly also mounted in said head, an operating gear assembly removably mounted in said handle, said spindle mounting comprising a barrel with removable front and rear bearings therein for 40 said spindle, and from which said spindle may be removed, a closure for the front end of said barrel adapted to be removed to permit removal of said spindle and a sliding lock adapted to hold a bur in said spindle and also adapted to form a closure 45 completely sealing the rear end of said head.

4. The combination with an instrument having a head, an intermediate section and a rear handle case with connecting means between the several parts and with the head having a cylindrical chamber and with cylindrical openings in the respective parts in which the cylindrical opening of the head communicates with the cylindrical chamber thereof, of driving parts in said instrument comprising a spindle both ends of which are 50 journalled in a removable barrel in the cylindrical chamber of said head, said spindle having a gear thereon, a gear assembly mounted in bearings forming a unit with the bearings adapted to be held in the cylindrical openings of said head and intermediate section, and an operating gear assembly mounted in bearings adapted to be held in the cylindrical opening of said rear handle case, said operating gear meshing with the gear of said gear assembly, said gear assembly and said 55 operating gear assembly having collars protruding from the outer surfaces of the bearings thereof, said collars positioning said gear and gear assembly in the instrument and providing means for locating and holding the gears in relative positions.

5. An instrument as described in claim 4 in which the connecting means of the respective parts are independent of the operating gear and gear assembly.

6. A dental tool comprising a hollow cylindrical head with an aperture in the upper end and having a tubular handle, a sleeve fitted to the head, a hollow bur holding spindle journaled for rotation within the sleeve, means rotatably holding the upper end of the bur above the spindle, means removably retaining the sleeve in the head, means independent of the sleeve retaining means removably retaining the spindle in the sleeve, said means adapted to be operated for the removal of the spindle from the sleeve without the removal of the sleeve or the retaining means therefrom from the head.

7. A dental tool comprising a hollow cylindrical head apertured at the upper end and having a tubular handle, a sleeve in said head, a hollow bur carrying spindle journaled for rotation and removably carried by said sleeve, means beyond the end of the spindle retaining said bur, a gear carried by the spindle, said sleeve in which the spindle is mounted having a flat side extending upward from the gear carried by the spindle, a shaft journaled in the tubular handle having a gear meshing with the gear on said sleeve, said spindle and sleeve adapted to be removed from said head as a unit without withdrawing the shaft gear from said head.

8. A dental tool, a cylindrical head having a tubular handle, a sleeve removably retained in said head, a bearing removably retained in said handle, a spindle adapted to hold a bur removably carried by said sleeve, means rotatably retaining said bur in said head beyond the end of the spindle, a drive shaft journaled in said bearing equipped with a gear, a gear carried by the spindle and adapted to be engaged by the gear on said shaft, said sleeve in which the spindle is mounted having a flat side extending upward from the gear carried by the spindle, said sleeve and spindle adapted to be removed from the head as a unit without withdrawing the drive shaft gear from said head.

9. A dental tool, a cylindrical head having a tubular handle, a unit in said head comprising a removable bearing in which a gear driven bur holding spindle is removably journaled, means retaining the unit in said head, said unit having a flat side providing access to the gear thereof, means rotatably retaining a bur in said spindle in said head and engaging the bur beyond the inner end of the spindle, a unit in said tubular handle comprising a bearing in which a shaft is journaled, a gear on said shaft engaging the gear driven spindle, and a section adapted to be secured to the tubular handle equipped with a drive shaft, said section, when secured to said handle, retaining the said unit in place in said handle.

10. A dental tool as described in claim 7 in which the shaft is journaled in a bearing in the handle and carries a gear at the outer end of the handle, and an angular attachment is also

removably attached to the end of the handle having a shaft journaled therein, also carrying a gear adapted to mesh with the gear on the shaft in the end of the handle, said shafts and bearings in the handle and attachment being removable as units, respectively. 5

11. A dental tool as described in claim 7 in which the shaft is journaled in a bearing in the handle and carries a gear at the outer end of the handle, and an angular attachment is also removably attached to the end of the handle having a shaft journaled therein, also carrying a gear adapted to mesh with the gear on the shaft in the end of the handle, said shafts and bearings in the handle and attachment being removable as units, respectively, and in which the outer stationary parts of said bearings only engage the handle and attachment with all movable parts suspended therein with sufficient clearance to prevent wear of said handle and attachment. 15

12. A dental tool as described in claim 7 in which the shaft is journaled in a bearing in the handle and said shaft and bearing may be removed as a unit, said shaft and bearings mounted with all moving parts suspended in said handle and spaced apart therefrom, preventing wear of the handle. 25

13. A dental handpiece having a head with a handle removably attached thereto, a spindle 30 mounting removably and slidably held in said head, said spindle having a gear thereon and said spindle mounting having a flat side extending upward from the gear on the spindle therein, an operating gear assembly removably and slidably 35 mounted in said handle, in which the gear thereof meshes with the gear of said spindle, and means locking the inner end of a bur in said spindle in said head.

14. A dental handpiece as described in claim 13 40 having a closure for the lower end of said spindle mounting adapted to be removed therewith.

15. A dental handpiece as described in claim 13 45 having a closure for the lower end of said spindle mounting adapted to be removed therewith, said closure also adapted to be removed from the spindle mounting with the spindle mounting in the head in order to remove said spindle from the mounting therefrom.

16. A handpiece as described in claim 13, in 50 which said spindle and gear assembly mountings space all moving parts away from the head and handle.

17. A handpiece as described in claim 13 in 55 which the spindle and gear assembly mountings are provided with bearings, and in which said bearings are readily removable from the head and handle with the spindle and gear assembly mountings and as separate and independent units.

WALTER JOHN TERRY. 60
